UNITED STATES PATENT OFFICE.

JOHN R. HALL, OF MERIDEN, CONNECTICUT.

DESIGN FOR A SERVING TRAY.

Application filed September 29, 1926. Serial No. 19,198. Term of patent $3\frac{1}{2}$ years.

To all whom it may concern:

Be it known that I, JOHN R. HALL, a citizen of the United States, residing at Meriden, county of New Haven, and State of Connecticut, have invented a new, original, and ornamental Design for Serving Trays, of which the following is a specification, reference being had to the accompanying drawing, forming part thereof.

Fig. 1 is a top plan view of the serving tray showing my new design.

Fig. 2 is an end elevation thereof.

I claim:

The ornamental design for a serving tray as shown.

JOHN R. HALL.
